[57] CLAIM

The ornamental design for a rod for hairdressing or similar article, substantially as shown and described.

DESCRIPTION

FIG. 1 is a perspective view of a rod for hairdressing or similar article showing our new design;

FIG. 2 is a front elevational view thereof;

FIG. 3 is a top plan view thereof, the bottom side being the same in appearance as the side shown;

FIG. 4 is a rear elevational view thereof;

FIG. 5 is a left side elevational view thereof;

FIG. 6 is a right side elevational view thereof;

FIG. 7 is an exploded front elevational view thereof with the attached elastic string being elongated;

FIG. 8 is an exploded top plan view thereof with the attached elastic string being elongated; and

FIG. 9 is a top plan view of a rod for hairdressing or similar article showing a modified form of our new design.
